UNITED STATES PATENT OFFICE.

CHARLES A. BUETTNER, OF NEW YORK, N. Y.

SLIDE.

1,083,985.

Specification of Letters Patent. Patented Jan. 13, 1914.

Application filed March 29, 1913. Serial No. 757,689.

To all whom it may concern:

Be it known that I, CHARLES A. BUETTNER, a citizen of the United States, residing at 228 Ridgewood avenue, in the county of 5 Kings, city and State of New York, have invented certain new and useful Improvements in Slides, of which the following is a specification.

This invention relates to slides to be used 10 with exhibiting machines, motion picture apparatus, &c., and has for its chief object to provide a slide having cut out lettering or characters which will not catch into the slide carrier when put in the machine.

15 Other objects are to greatly reinforce the slide and to simplify and cheapen the cost of manufacture, &c., all of which objects are accomplished by the combination and construction of parts hereinafter more particularly described and claimed.

In the accompanying drawings: Figure 1 represents a front elevation of a slide embodying my invention; Fig. 2, a rear elevation of the same; Fig. 3, a longitudinal 25 section on the line 3—3 of Fig. 1; Fig. 4, a cross-section on the line 4—4 of Fig. 1; and Fig. 5, a view in front elevation of the three parts of the slide arranged adjacent each other.

30 Referring now in detail to the drawings, 1 designates a reinforcing frame of sheet iron or other suitable material and is provided with an elliptically shaped opening 2 for the passage of light and to permit 2 part of the facing 3 to be depressed therein.

The front or facing 3 of thin sheet metal is provided with a portion 4 out of which are cut letters or other characters or figures, this portion, when the slide is assembled, 40 registering with the opening 2 in the frame 1.

45 5 designates a sheet of mica or other suitable material which may be tinted as desired and which is arranged between the facing 3 and the frame 1, extending completely over the opening 2 and behind the portion 4.

In practice the sheet of mica 5, or other suitable material and the facing 3 are

superimposed on the frame 1, with the edges 50 of the facing 3 overlapping the edges of the frame 1 and with the corners of the facing 3 cut out as at 6. Next the overlapping edges of facing 3 are bent over the edges of frame 1 and tightly pressed against the 55 rear thereof, and portion 4 of the facing 3 being in the same operation depressed through the opening 2 in the frame 1. The exact degree of the depression of the portion 4 may be regulated as desired, but I 60 prefer to depress it until its near face is on a plane with the rear face of said frame 1, thus fully protecting the letters, &c., and preventing it from catching in the carrier. Such depression may of course be made also 65 in a separate operation. The cut out portions 6 of the part 3 will allow the edges 7 of the facing 3 to be folded smoothly on the rear of frame 1, without wrinkling, crushing, &c., at the corners. 70

It is to be noted that by depressing the portion 4 through opening 2 the lettering, &c., will be out of the way of possible harm and accident in the carrier. Also the edge of this depression is gradual, not abrupt, 75 hence nothing will catch on the edge of the depression, thus the objection of a separate folded marginal strip is avoided.

It is quite obvious that slight changes and alterations may be made in the construction and arrangement of my device, of which only the preferred form is illustrated and described in this application and it is my intention and desire to include all such alterations and changes in the following 85 claims.

Having thus described my invention, what I claim as new and desire to secure by Letters Patent is:

1. A slide comprising a reinforcing frame 90 provided with an opening, in combination with a sheet metal facing provided with perforations which are in alinement with said opening and having its edges overlapping the edges of said frame and pressed 95 against the rear thereof.

2. A slide comprising a reinforcing frame having an opening and a coloring medium

superimposed thereon, in combination with
a sheet metal facing firmly held in super-
imposed relation on said coloring medium
and frame and having a perforated portion
registering with said opening, the said per-
forated portion being depressed through
said opening.

In testimony whereof, I have signed my
name to this specification in the presence of
two subscribing witnesses.

CHARLES A. BUETTNER.
